UNITED STATES PATENT OFFICE

CHESTER A. SEASE, OF HARRISBURG, PENNSYLVANIA, ASSIGNOR OF ONE-HALF TO
PRESTON CROWELL, JR., OF HARRISBURG, PENNSYLVANIA

BUSHING REMOVING AND REPLACING TOOL

Application filed April 24, 1928. Serial No. 272,501.

This invention relates to improvements in tools for removing and replacing bushings.

The primary object of this invention is the provision of an improved tool to facilitate the removal and replacing of bushings, particularly well adapted to avoid battering and distorting the bushing during the placement thereof.

A further object of this invention is the provision of an improved bushing removing and replacing tool, which includes detachable portions adapted to fit within the bushing and at an end of the bushing, and by means of which the bushing tool may be made available for driving bushings of various sizes.

A further object of this invention is the provision of an improved bushing tool which will permit the driving of bushings into place, with facility; with the avoidance of poor fit and eccentricities.

Other objects and advantages of this invention will be apparent during the course of the following detailed description.

In the drawing, wherein for the purpose of illustration is shown only a preferred embodiment of this invention,

Figure 1 is a perspective view of the improved tool.

Figure 2 shows the tool, partly in section, operating on a bushing for placing the latter in a machine-part.

Figure 3 is a view of the bushing tool with the parts arranged to drive a relatively long bushing in a protected relation; the bushing being of a size smaller than that illustrated in Figure 2, and the parts of the tool being arranged accordingly.

Figure 4 is a side elevation of the tool as provided for the bushing of Figure 3.

Figure 5 are end views of various sized discs adapted to be used selectively as driving or protecting discs, according to the size of bushing being operated upon.

In the drawing, wherein similar reference characters designate corresponding parts throughout the several views, the letter A may generally designate the improved tool, which may comprise a driving post or handle 10, adapted to detachably receive driving and protecting members 19, 20, and 21, in a

clamped relation by nut or pilot shaft means 13.

It is the preferred structure of the tool, that the same have a pair of annular discs or flanges thereabout, between the ends thereof, preferably of a detachable nature, one of which flanges or discs is smaller in diameter than the other; the smaller flange being adapted to fit into the bushing in a protecting relation at the end thereof, and the other adapted to engage externally at the end of the bushing to act as a driver. To this end the driving post or handle 10 preferably comprises an elongated body 15, preferably polygonal in cross section, having a reduced screw threaded shank 16 at one end thereof, and providing an abrupt shoulder 17 at the juncture of the shank 16 with the body 15. With each tool it is preferred to provide a set of ring-shaped bushing operating discs 19, 20, 21, etc., each provided with an opening 22 therein, to permit the screw threaded shank to be freely slipped therethrough.

The means 13 preferably consists of an elongated pilot extension, having a screw threaded socket 25 inwardly from one end thereof adapted to receive the screw threaded shank 16 of the driver 10, and the end of which pilot extension 13 is adapted to engage against the operating discs or rings to clamp them firmly against the shoulder 17 in a rigid relation on the tool.

Assuming that a bushing B of a known internal and external diameter is to be driven into the opening 30 of a machine part B, a ring-shaped disc 19 is selected, the outer diameter of which is the same as the external diameter of the bushing B, and it is first placed upon the screw threaded shank 16 and moved thereon into abutment with the shoulder 17. A second disc 20 is then selected, having an external diameter slightly less than the internal diameter of the bushing B, and it is placed upon the shank 16 and moved into abutment against the facing end of the disc or ring 19. The pilot nut 13 is then screw threaded upon the shank 16 into clamping engagement against the disc 20, to clamp the discs 19 and 20 into a firm relation on the tool. The pilot extension of the tool is then moved

into the bushing, and the disc 20 is moved into the end of the bushing opening to protect the end of the bushing, and of course the marginal portion of the disc 19 which projects beyond the outer periphery of the disc 20 abuts the end edge of the bushing B, to facilitate the driving of the bushing in a manner which will be perfectly apparent. Of course, the portion 20 protects the bushing passageway from being battered, and avoids the necessity of reaming such as is sometimes required when driving bushings with ordinary tools. In this respect it is to be noted that the disc 19 may be referred to as a driving disc, ring, or flange or enlargement, and the disc 20 acts as a protecting flange, disc, ring, or enlargement.

In some instances, thin or long bushings are provided, such as the bushing D, shown in Figure 3 of the drawing. The bushing D has been purposely shown smaller in diameter than the bushing B, in order to show the versatility of the tool A in its application to bushings of various sizes. Assuming the passageway in the bushing D is the next size smaller than the passageway in the bushing B, it is then necessary to replace the disc 19 with the disc 20; the latter now becoming the driving disc, and a smaller protecting disc 21 is then slipped upon the screw threaded shank and clamped in place, to act as a protector within the bushing D. Inasmuch as the bushing D is relatively long, a plurality of discs 21 are placed upon the shank 16, and retained in spaced relation by a spacing sleeve 23, which is also shown in Figure 5 in end view; the spacing sleeve 23 being of smaller diameter than the internal diameter of the bushing B, and smaller in diameter than the external diameter of the protecting disc or ring 21. The parts 20, 21 and 23 are maintained in a clamped relation upon the shank 16 and the tool A by means of the pilot nut 13, as is readily apparent from the drawing.

From the foregoing description of this invention it is apparent that a bushing removing and replacing tool has been provided, which enables an expeditious operation in the replacing or removing of bushings. The removing operation is of course accomplished by forcing the bushing thru the part on which it is placed, inasmuch as no part of the bushing tool is of a larger diameter than the passageway through the part on which the bushing is mounted. In fact, it is preferred that both the driving and protecting discs be greater in diameter or cross dimension than any other section of any other part on the tool, including both the driver 10 and the pilot extension or nut 13. Of course the pilot extension 13 may be an ordinary nut if desired, but in the form shown it acts as a guide in placing the bushings in the machine

part, or in placing the tool in the bushing, and it protects the thread of the shank 16.

Various changes in the shape, size, and arrangement of parts may be made to the form of invention herein shown and described, without departing from the spirit of the invention or the scope of the claims.

I claim:

1. In a bushing replacing and removing tool the combination of a supporting body comprising a pair of elongated parts, means to adjustably clamp said parts together, and a plurality of relatively stepped discs of different sizes assembled upon the body and clamped in rigid relation thereon between and by said clamping parts, with the latter extending at opposite ends of the tool beyond said discs. 75

2. In a bushing removing and replacing tool the combination of an elongated driver, a plurality of independent discs of different diameters, and means for detachably clamping the discs on the body in adjacent immovable relation thereon, whereby one of the discs may operate as a protector within an end of the bushing and the other disc operate as a driver against an end edge of the bushing. 85

3. In a bushing removing and replacing tool the combination of an elongated driver body, a pair of relatively detachable discs of different diameters, and means for clamping the discs in a rigid relation at an end of the body whereby one of the discs may act as a protector within a bushing and the other disc act as a driving abutment against an end of the bushing. 95

4. In a bushing tool of the class described a body having a reduced screw threaded shank at an end thereof to provide a shoulder at the juncture of the shank with the body, a ring-shaped disc received on said screw threaded shank against said shoulder, and a nut on the screw threaded shank for adjustment against the disc to detachably hold it rigid on the body. 105

5. In a bushing tool of the class described a body having a reduced screw threaded shank at an end thereof to provide a shoulder at the juncture of the shank with the body, a ring-shaped disc received on said screw threaded shank against said shoulder, a second annular disc smaller than and detachable of the first ring disc disposed on the screw threaded shank and in abutment with the first mentioned disc, and a nut in the screw threaded shank clamped against the second disc to hold said discs rigid on the body. 115

6. In a bushing removing and replacing tool the combination of a pair of elongated parts having a screw threaded connection with facing shoulders therebetween, and bushing driving and protecting discs clamped rigid between said shoulders. 125

7. In a bushing removing and replacing tool set the combination of an elongated driving body having a reduced screw threaded shank thereon, a nut for the screw threaded shank, and a plurality of ring-shaped discs of different sizes to be placed on the shank and clamped thereon by the nut.
8. In a bushing removing and replacing tool set the combination of an elongated driving body having a reduced screw threaded shank thereon, a nut for the screw threaded shank, a plurality of ring-shaped discs of different sizes to be placed on the shank and clamped thereon by the nut, and a spacer sleeve for placement between said discs, on the shank, and of smaller diameter than the discs, to space a plurality of discs of the same size from each other longitudinally of said shank.
9. In a bushing removing and replacing tool the combination of an elongated driver, a detachable driving flange on the driver, a detachable protector of smaller diameter than the driving flange on the driver adjacent the driving flange, and means to hold said driving flange and protector in clamped assembled relation on the driver.
10. In a bushing removing and replacing tool the combination of an elongated driver, a detachable driving flange on the driver, a detachable protector of smaller diameter than the driving flange on the driver adjacent the driving flange, a second protector on the driver, means spacing the second protector from the first protector, and means to clamp the driving flange, the protectors and the spacer on the driver.
11. A bushing operating tool comprising an elongated body having a reduced screw threaded shank providing a shoulder, a ring-shaped driving enlargement on the shank in abutment with said shoulder, a plurality of bushing protecting rings of the same external diameter on the shank, a spacer sleeve between said protecting rings to hold them in spaced relation, the spacer sleeve being smaller in diameter than the protecting rings, an elongated pilot extension having a screw threaded socket to receive the screw threaded shank therein to clamp the driving enlargement above mentioned and the rings on the shank in a rigid assembled relation.
12. In a bushing tool the combination of an elongated body, an elongated pilot extension, means detachably connecting the pilot extension on the body in an axially aligning relation therewith, and means on the tool clamped rigidly and between the body and pilot extension comprising an annular part adapted to fit within the bushing at an end thereof and an annular part adapted to fit against an end edge of the bushing to permit the driving of the bushing.
